Primary Examiner — Ricky Pham

(74) Attorney, Agent, or Firm — Panasonic IP Management; Kerry S. Culpepper

(57) **CLAIM**

I claim the ornamental design for an induction heating cooker, as shown and described.

DESCRIPTION

FIG. 1 is a front perspective view of an induction heating cooker of the present invention;

FIG. 2 is a front view thereof;

FIG. 3 is a top view thereof;

FIG. 4 is a bottom view thereof;

FIG. 5 is a first side view thereof;

FIG. 6 is a second side view thereof; and,

FIG. 7 is a rear view thereof.

The broken line showing of induction heating cooker is included for the purpose of illustrating environment and forms no part of the claimed design.
